Primary Examiner — Mary Ann Calabrese(74) *Attorney, Agent, or Firm* — Robert F. Zielinski(57) **CLAIM**

I claim the ornamental design for a study carrel, as shown and described.

DESCRIPTION

FIG. 1 is a side, top perspective view of a study carrel showing my new design.

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

In the drawings, the broken lines show portions of the study carrel that form no part of the claimed design.
